DESIGN FOR A DRESS

Jo Wise Meyer, New York, N. Y.

Application February 11, 1938, Serial No. 75,079

Term of patent 3½ years

To all whom it may concern:

Be it known that I, Jo Wise Meyer, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress as shown, of the checkerboard arrangement of the inserted flaps on the sleeves and front waist, as shown.

I claim:

The ornamental design for a dress, substantially as shown, and described.

JO WISE MEYER.
